UNITED STATES PATENT OFFICE

LOUIS H. MORIN, OF NEW YORK, N. Y., ASSIGNOR TO DOEHLER DIE-CASTING CO., A CORPORATION OF NEW YORK

METAL FURNITURE

Application filed June 30, 1927. Serial No. 202,617.

My invention has particular reference to metal furniture, one of the objects being to make it possible to construct a particularly handsome, ornate, rugged, ornamental piece 5 of furniture, which is adapted to be "knocked down" or disassembled to provide for the more convenient shipment thereof, and for the further provision, whereby, through standardization of parts, a marred or injured 10 part may be readily replaced by a new part.

The more common practice among manufacturers of metal furniture at the present time is to assemble the articles of furniture in complete form at the factory, ready for 15 use by the purchaser, by such means as welding or riveting in order that permanent fastening may be obtained and in order that a sufficiently solid and durable piece of furniture may be produced. Such constructions 20 have been difficult to fabricate, expensive and unsatisfactory because of the impossibility of replacing a damaged or injured part.

Difficulty has, moreover, been experienced 25 in providing satisfactory fastening means between the various parts. Bolts or rivets in the sheet metal for the direct support of strains are unsatisfactory because of the fact that they soon become loose. Welding is unsatisfactory because of the defacing of the 30 surfaces at the points where the welding occurs. Likewise in the case of welded or riveted members, it is not possible to remove an injured, marred or damaged member for replacement by another without extensive and elaborate rebuilding and refinishing of the 35 article.

In accordance with my invention, and as a 40 means for overcoming these and other disadvantages, I have produced a new and useful system of construction for articles of metal furniture. By this construction I am enabled to produce articles having the utmost rigidity, a rigidity equal to or superior than that produced in any other type of furniture construction, whether in wood or in metal, and

a construction which at the same time allows of ready dismantling. These advantages I obtain in an article comprising sheet metal parts by a new and useful construction of the joints, corners and angles of the article of 50 my invention. The construction of my invention is particularly adapted to the production not only of extremely firm, solid, joints between members, for the simultaneous stiffening and strengthening of the article of 55 furniture as a whole, but for the production of a sightly, handsome article. The device of my construction utilizes sheet metal members for the panels of the article of furniture, and further utilizes upright members adapted to be firmly united to the panel members by a combined clamping and locking action, 60 whereby the upright member, while readily detachable at need, makes an extremely firm, stiff, union with the panel members. The 65 upright members are also adapted to ready modification according to the period or style of the furniture to be produced. My invention further provides drawer members of 70 maximum beauty and efficiency, by means which render inconspicuous the unavoidable cracks between successive drawers, and the construction is further adapted to the smooth and easy sliding of the drawers, and to the 75 convenient finishing of the surfaces by a baked enamel.

The nonresonant qualities of the top and other members are obtained without sacrifice of the ease of application of the baked enamel. A substantial portion of the strength of 80 the article is obtained by interlocking of the top member with the uprights and side panels, and a further substantial portion by the attachment of the bottom panel underneath 85 the drawers, combined with top and bottom front-rails.

I shall now describe a preferred embodiment of my invention, illustrated in the accompanying drawings, and shall thereafter point out my invention in claims, from 90

which, and the preceding and following description, other objects of my invention will appear, as well as the structural details.

In the drawings:

Fig. 1 is a view in front elevation, partly in section of a preferred embodiment of the article of my invention;

Fig. 2 is a view in vertical side section of the same embodiment;

Fig. 3 is a sectional view of the front rail, drawer, top, and back construction of the same embodiment;

Fig. 4 is a view in horizontal section of a back upright member of my invention;

Fig. 5 is a view in vertical section of the bottom panel member and leg member of the same embodiment;

Fig. 6 is a perspective view, partly in section, of the fronts of a plurality of drawers of the same embodiment, and

Fig. 7 is a horizontal view in section of the front rail member of the same embodiment.

For the purpose of illustration, I have shown my invention as embodied in a piece of metal furniture of the type known as a chiffonier, or chest of drawers. The article is designed to include a plurality of drawers, and may be surmounted by a finishing rail at the back as indicated, or may be surmounted by a mirror of any suitable pattern. The article of my invention may be considered as composed of two main elements, the frame, or cabinet, and the group of drawers. For purposes of convenience, I shall describe the frame first, then the drawers, and thereafter the assembled combination.

The frame of the article of my invention consists of upright members, and attached panel members, formed of metal, and appropriately lacquered or painted. Broadly these portions consist of four stiff, metal, corner-upright members, side panels, a back panel, a bottom panel, and a top.

Referring to the drawings, I provide a pair of front upright members 1 and a pair of back upright members 2. Between the respective right hand and left hand members of each pair are attached the side panel members 3 formed of sheet metal, and fastened by means to be later described. Between the back upright members 2 is provided a back panel member 4 similarly attached to the upright members 2. A bottom panel member 5 is provided and appropriately attached to the upright members and the panel members 3 and 4. A top member 6 is likewise provided and suitably attached to the upright members and the side and back members.

The back upright members 2 are desirably formed of substantial strips of metal which may desirably have the section indicated in Fig. 4. These members may be made of rolled steel, or may be made of cast metal of any suitable type. They are desirably drilled

and tapped at suitably frequent intervals for the reception of clamping screws 7 as indicated. A clamping member 8 is provided having a shape as indicated in Fig. 4, and drilled for register with the holes in the member 2 for the passage of the clamping screws 7. The side edges of the panel members 3 and 4 are bent at 9, as indicated, at an angle of approximately 45° and are thereby adapted to cooperate with the inner surface of the member 2 for contact therewith, and with the surface of the member 8, which by means of the screw 7 is clamped firmly against them and provides a very stout, durable, substantial fastening between the side and back panel members and the main upright member.

The upright members 2 are further provided with leg members 11. These members may take any desired form, simple or ornate, of any desired architectural school, according to the period of design which it is desired to follow in the article of furniture. These leg members are desirably equipped with casters 12, they may be formed of cast metal or of other suitably worked material, and they are desirably attached to the member 2 by rivets 14 as indicated. This construction provides a plurality of stout structural members which give ample strength for the piece of furniture.

The front upright members 1 are in general similar to the back uprights 2 but are slightly modified from the design thereof since the side panels 3 only are clamped thereto. The front of the article of furniture is provided by the drawer fronts, and it is found convenient to dispense with a "ladder" for separation between the drawers. Accordingly the front upright members are attached to the panel members 3 by a clamping provision similar to that provided for the back members 2. This construction is shown in Fig. 7 in which the upright members 1 are shown in top end view and a clamping member 15 is provided and held in place by screws 16 passing therethrough and threaded into tapped openings in the member 1. Front leg-members 11 with casters 12 are similarly provided and riveted to the upright members 1 in a manner similar to the leg-members 11 attached to the members 2. These leg-members 11 may be similar to the leg members attached to the back uprights, or they may, if desired, be of a different pattern or more ornate according to the requirements of the period of design followed. This assemblage of members provides back, sides, legs and uprights in a very stout construction.

The bottom edges of the panels 3 and 4 are reversely bent as indicated in section in Figs. 1, 2 and 5. A portion 17 is bent inwardly at the lower edge of the respective panels. A further portion 18 is bent upwardly, and a still further portion 19 is again bent in-

wardly. By this means a reinforcing channel and ledge are formed at the bottom of the three respective panels.

The bottom panel member 5 is formed at its edges to provide a square truss construction as indicated at 21, having an inturned flange beneath this panel 5 (Figs. 1, 2 and 5), thus providing a strong tubular reinforcement on this panel. The truss portion 21 is adapted to enter the channel formed by the members 17 and 18, and may fit with a friction fit therein. Perforations may be provided at 22 as indicated, and suitable bolts 23 may be inserted therein. By this means an extremely stout, rugged, durable, attachment is provided between the metal of the back and side panel members, and the metal of the bottom panel member 5. A bottom front rail 24 is provided, around which the metal of the bottom panel 5 is bent as indicated in Fig. 2. The ends of the cross rail 24 are desirably bent inwardly at right angles and attached to the upper ends of the front leg-members 11 by screws 25 as indicated, and the bent over ends desirably rest upon ledges formed in the front leg-members 11. By this means the front legs are fastened together and very stout support for the edges of the panel member 5 is provided.

The top member 6 desirably consists of two sheets of metal 26 and 27 with deadening material 28 positioned between. The edges of the sheets are desirably bent to simulate the customary beveling or beading of a board top, and to provide the appearance of the customary thickness, as well as additional strength. A front rail member 29 is provided, formed as shown in Fig. 7, and adapted to be attached to the front upright members 1 by screws 31 as indicated. The lower sheet member 27 is desirably bent at its front edge as shown in Fig. 3, to provide a ledge 32, and portions 33 surrounding the top rail 29 and contacting with the inner surface of the sheet. By this means the sheet 27 is firmly attached to the front rail 29. The side edges are desirably bent downward as indicated at 34 in Fig. 1.

The top sheet 26 is desirably formed with the beading 35 around the front and sides, and with a downwardly bent portion 36. A further portion 37 is bent inwardly, cooperating at the front with the ledge 32, and at the sides with the downwardly bent portion of the sheet 27. The cooperation of the members 37 with the appropriate portion of the sheet 27 produces an interlocked top member of great strength. The filler member or deadening material 28, may desirably be formed of heavy sheet asbestos, or asbestos board, or other suitable material, and is desirably inserted during the assembling of the members 26 and 27, after which the back edge 38 of the top sheet 26 may be bent downward and under the member 27, and thence

downward on the back panel 4, as indicated in Fig. 3, thereby locking the respective members firmly together and completely enclosing the deadening material 28.

A back rail member 39, desirably formed of angle bar, in iron or other suitable material, is provided and the ends formed and bent as indicated in Fig. 3. The cross rail 39 is desirably attached to the tops of the uprights 2 by screws 41 as indicated, and the back panel member 4 is desirably attached at its upper edges by additional screw members 42, which also hold in place the edge portion 38 of the top sheet 26. By means of the attachment of the front rail 29 and the back rail 39, the top member 6 is firmly held to the panels and uprights, and an extremely stout, durable, rigid frame member is produced.

A back ornament 43 may be attached as desired at the rear edge of the top member 6. This may take the form of the simple member indicated, or may be any suitable form of mirror or other suitable ornamental construction as desired. It may be held in place by screws 44 passing through the back rail 39 and the top member 6. The screws serve the additional purpose of attaching the back member 6 firmly to the back rail 39 and provide additional strength.

Drawer slides 45 are likewise provided. For ease of movement and silence, the drawer slides 45 are preferably formed in wood and are desirably adapted to be inserted after the substantial completion of the article. Accordingly metal clip members 46 are provided and attached to the interior of the side members. The members 46 may be attached directly to the side panels 3 by appropriate means, or they may preferably be attached to the clamping members 8. They may be an integral part therewith or may be welded thereto or otherwise attached as desired. A sufficient number of drawer slides 45 are provided and positioned at appropriate heights for the cooperation with the grooves in the drawers.

The drawer members 47, comprising the second main portion of my invention are also desirably formed of sheet metal. The fronts 48 of the drawers may be formed of separate sheets of metal suitably embossed to provide the usual panel appearance. The upper edges of the drawer front members are desirably bent inwardly to provide ledges 49 to simulate the appearance of thickness associated with the customary wooden drawers, and for the further provision of greater strength in the construction. The bottom edges are desirably formed with a bead or rib 51, which may extend further forward than the bead or rib 52 formed as a part of the ledge 49. From the bottom of this rib 51 there is a rearward upwardly inclined extension having a flat marginal edge underlying the sheet metal bottom of the drawer, there-

by providing a clearance ridge for this bottom, as well as a corner reinforcement. This construction is shown in greater detail in Fig. 6.

5 This construction is particularly desirable because of the fact that the substantial bead 51 casts a shadow upon the smaller bead 52, and obscures the crack which necessarily is provided therebetween for purposes of ease 10 in sliding of the drawers. This construction provides a very handsome drawer front. Beads 53, shown in Fig. 2, may also be provided so that the upper edge of the drawer simulates the appearance of the "ladder" construction which is common to the usual pattern of such article of furniture. The bottom, sides and back of the drawers 47 are also desirably formed of sheet metal and may be attached to the fronts 48 in any desired way 15 as by riveting, folding or other means well known to those skilled in the art of the working of sheet metal. Guideways 54 are desirably formed in the sides of the drawers as indicated, for cooperation with the guide- 20 rails 45, to carry the weight of the drawers. Additional strengthening means 55 are desirably provided at the centers of the bottoms of the drawers 47. These may take the form of U-shaped metal truss members appropriately attached, or may have a W shape as desired, according to the amount of strength 25 required. They are desirably made of such height as to pass above the ledge 49 of the drawer beneath.

30 35 The construction of the drawers is suitable to the application of such methods of forming as the ordinary bending operations in metal working, or to the forming by stamping in dies, also of the usual pattern. The drawer members may desirably be constructed according to the usual dimensions and methods for the ordinary type of metal drawer, certain of the inventive features, being formed in the particular arrangement of 40 parts in the fronts of the drawers and in the strengthening truss underneath.

45 By this construction of the article of my invention, the various members may conveniently be formed and prepared for assembling 50 by appropriate bending of the sheet metal parts, as well as appropriate manufacturing operations upon the heavier metal parts. Any 55 article of furniture is desirably finished by the application of a coat of paint, lacquer, or enamel, and in the case of metal furniture the finish is desirably one which imitates the graining of wood. The article of my invention may be finished before or after assembly, by the application to the surfaces, of an appropriate coating of finish, which may desirably imitate wood grain. It has been found 60 desirable to apply a baked enamel for the finish, because of the greater durability and more handsome appearance of a baked finish, as 65 compared to the usual air dried finish, as

well as the much greater speed with which the finish can be completed and hardened. Accordingly the baked finish may be applied to the various parts in the usual way. When so applied, the wooden drawer slides 45 are to be left out of the clips 46, in order that they may not be affected by the heat of the baking oven. In this way the drawers, and the side back and bottom panel members, may be lacquered and baked without difficulty since they consist entirely of metal parts. Likewise, the top member 6, may be grained, enameled, and baked without injury because of the heat resisting character of the filler material 28. By this construction the article of my invention is particularly adapted to the application thereto of a baked enamel finish, and likewise to the incorporation therein of means for the deadening of resonance, and means for the smooth, easy, quiet sliding of the drawers, 85 since the wooden drawer slides may conveniently be inserted after the finishing of the article.

90 The article of my invention is assembled by means of well protected clamping devices, held in place by concealed screws and bolts. Accordingly there are no welds to deface the surfaces of the article, and the smooth, handsome appearance of the various members is preserved. Likewise, the various members 95 are attached by clamping means which may readily be disassembled by simple tools. Thus in the event that a panel or part is damaged in the course of the service or life of the article, it may readily be removed, by disassembling the article. The parts are made to accurate dimensions and accordingly a new part is readily assembled with the other parts, to replace a damaged part, thereby restoring 100 the article to its original condition of serviceability. Either the upright members, the panel members, the drawer members or other parts are readily replaced by simple operations, within the skill of the ordinary person.

105 The article as herein disclosed is constructed with drawers of the same size, and accordingly the article is not adapted to be packed for shipment in the minimum space. Alternatively, however, the drawers may be adapted to nesting, as disclosed in the application of Antoine Vericel, Serial No. 191,610, filed May 16th, 1927, thereby adapting the article to shipment in a disassembled state, in a minimum bulk of package. Thus the article may be erected as hereinbefore disclosed, for shipment to the user, whereby the article is ready for immediate use after unpacking. Alternatively, the article may be shipped in 110 a disassembled state, thereby occupying somewhat less bulk, and may thereafter be assembled upon receipt by the purchaser, the method of assembling being obvious from the drawings, and requiring only the proper 115 position of the respective members and the 120

insertion of the bolts and screws, whereafter the drawers may be positioned upon the slides.

By the construction of my invention I have thus produced a handsome, stout, rugged, article of furniture produced mainly from metal parts, of the greatest simplicity, adapted to production at a minimum cost and of assembling into a finished article with ease and adapted to the interchangeable replacement of injured parts, or for the changing of parts to vary the style or period of the article of furniture.

While I have shown but a single embodiment of the device of my invention in the accompanying drawings and description, it is capable of various modifications without departing from the spirit thereof and it is desired therefore that only such limitations shall be imposed thereon as are required by the prior art or indicated by the appended claims.

I claim as my invention:

1. In a cabinet as an article of furniture comprising panels and a corner reinforcement at the joint between adjacent panels, the combination of an internally channeled metal frame part forming a rigid outer corner piece for the cabinet having a single inwardly opening inner channel defined and formed by lateral wings with their inner surfaces along their edges disposed at a flaring angle relatively to each other, adjacent sheet metal panels in planes at an angle to each other in line with the inner flaring surfaces formed by the wings of the channel along the edges of these wings and having adjacent bent edge margins shaped to conform to the contour of the channel in the corner piece and fitting into this channel in contiguous relation with one another, and securing means carried by the corner piece and engaging with the said bent edge margins to cooperate with the flaring wing portions of the channel for firmly holding these bent edge margins in the channel for thereby joining the panels together and reinforcing them at the corner joint.

2. In a cabinet as an article of furniture comprising panels and a corner reinforcement at the joint between adjacent panels, the combination of an internally channeled metal frame part forming a rigid outer corner piece for the cabinet having a single inwardly opening inner channel defined and formed by lateral wings with their inner surfaces along their edges disposed at a flaring angle relatively to each other, adjacent sheet metal panels in planes at an angle to each other in line with the inner flaring surfaces formed by the wings of the channel along the edges of these wings and having adjacent bent edge margins shaped to conform to the contour of the channel in the corner piece and fitting in the channel with their

edges in abutting relation along the bottom of the channel, a clamp member fitting against the inner sides of the abutting bent edge margins of the panels, and a securing stud carried by the corner piece projecting inwardly from the bottom of its channel between the edges of the panels through the clamping member and having a head which presses the clamping member tightly against the bent edge margins of the panels to cooperate with the flaring wings of the channel so that thereby the panels are firmly secured to the corner piece by their bent edge margins.

3. In a cabinet as an article of furniture comprising panels and a corner reinforcement at the joint between adjacent panels, the combination of an outer metal corner piece forming a rigid frame part having a single inwardly opening inner channel with a flat bottom and flat flaring wing portions at right angles to each other and joining with the flat bottom at a re-entrant angle of 45° so that thereby this channel is formed between and by means of these flat flaring wing portions, sheet metal panels in planes at right angles to each other in line with the respective inner flat surfaces of the wing portions of the channel and having 45° bends in adjacent marginal edge portions providing flat angular margins which enter the channel and conform respectively to the 45° angles therein formed by its respective wing portions, and securing means carried by the corner piece in the flat bottom of its channel and engaging with the adjacent angular edge margins of the panels to cooperate with the flat flaring wing portions of the channel for connecting the panels together and reinforcing the corner joint.

4. In a cabinet as an article of furniture comprising panels and a corner reinforcement at the joint between adjacent panels, the combination of an outer metal corner piece forming a rigid frame part having a single inwardly opening inner channel with a flat bottom and flat flaring wing portions at right angles to each other and joining with the flat bottom at a re-entrant angle of 45° so that thereby this channel is formed between and by means of these flat wing portions, sheet metal panels in planes at right angles to each other in line with the inner flat flaring surfaces formed by the respective wing portions of the channel and having 45° bends in adjacent marginal edge portions providing flat angular margins which conform to and fit into the channel with their edges in abutting relation along its flat bottom, a clamping strip having a flat surface fitting against the flat inner faces of the angular edge margins of the panels and fitting into their re-entrant angles, and a series of securing studs carried by the corner piece projecting inward from the flat bottom of its channel between the edges of the abutting edge

- 5 margins of the panels through the clamping strip and having heads which press the flat surface of the clamping strip tightly against the inner flat surfaces of the bent angular margins of the panels to cooperate with the flat flaring wing portions of the channel so that thereby the clamping of these angular margins in the angles of the channel firmly secures both panels to the corner piece.
- 10 5. The invention defined in claim 4, in which the clamping side of the said clamping strip has flat wing portions providing a clamping face formed with 45° salient angles which fit into the 45° bends of the margins of the clamped panels so that thereby the margin of each panel will be clamped at its angular bend and will also be clamped between flat surfaces at opposite sides of this angular bend.
- 15 6. In a cabinet as an article of furniture comprising a panel and a corner frame piece to which a marginal edge portion of the panel is connected, the combination of an outer metal corner piece forming a rigid frame part having in its inner side a channel with flat surfaces forming a re-entrant angle of substantially 45° , a sheet metal panel having an angularly bent edge portion providing flat surfaces at an angle fitting into the re-entrant angle of the channel and against its flat surfaces, a clamping strip having a clamping face with a salient angle and flat surfaces fitting into the angle of the bent edge portion of the panel and against its flat surfaces, and a series of headed studs carried by the corner piece at its inner side for firmly holding the clamping strip against the angularly bent edge portion of the panel to cooperate with the angular channel for thereby firmly securing the latter to the corner piece.
- 20 7. In a cabinet as an article of furniture comprising sheet metal panels in planes at right angles to each other connected together at their adjacent edges, the combination of a tubular reinforcement along the outer side of a margin of one of the panels formed in the same piece therewith, a reinforcing channel formed on the inner side of an outwardly extended margin of the other panel in the same piece therewith with one side of the channel in line with the panel and into which channel the said tubular reinforcement on the first-named panel fits for connecting the panels together, an inturned flange on the said reinforcement extending along the adjacent surface of its panel away from the margin thereof, a ledge formed on the edge of the channel of the other panel and superposed on the said flange, and securing means firmly attaching together the said ledge and the said flange and the body portion of the panel having the said flange on its tubular reinforcement.
- 25 8. In an article of furniture having a

70 drawer, a sheet metal drawer front of which the upper edge has a margin turned rearward horizontally and thence turned downward and extending forward towards the inner side of the drawer front at a lower level forming an inner hollow horizontal reinforcing ledge on the upper edge of the drawer front, and of which the lower edge of the drawer front has a margin extending below the drawer bottom and thence turned rearward and upward below the lower side of the drawer bottom so as to form a hollow clearance ridge below the front portion of the drawer bottom as well as a reinforcement for the lower front corner of the drawer.

75 9. In an article of furniture having a drawer, a sheet metal drawer front having in combination therewith a top edge reinforcement formed in the same piece therewith comprising an outer rib and an inner hollow ledge the top wall of which extends rearward horizontally from the top of the rib and the lower wall of which extends forwardly at a downward inclination towards and with its edge substantially adjacent the inner shoulder formed by the rib, whereby a substantially triangular hollow stiffening rail is provided along the top edge of the sheet metal drawer front.

80 10. In an article of furniture having a drawer, a sheet metal drawer front having in combination therewith a lower front corner reinforcement formed in the same piece with the front comprising a marginal extension of the front below the drawer bottom which is formed into a lower front rib and at the bottom of this rib has a rearwardly extending upwardly inclined flange portion below the lower side of the drawer bottom, whereby a hollow reinforcing and clearance-providing ridge is formed below the drawer bottom at the front.

85 11. In combination with the invention defined in claim 1, the said securing means including a series of securing studs carried by the corner piece projecting inwardly from the bottom of its channel and having securing heads upon their inner ends.

90 12. In combination with the invention defined in claim 3, the said securing means including a series of securing studs carried by the corner piece projecting inwardly from the flat bottom of its channel and having securing heads upon their inner ends.

95 13. In an article of furniture, the combination of an outer rigid corner frame piece formed of metal, this frame piece forming a channel which has a flat bottom portion and a pair of flat lateral wing portions each of which joins with the flat bottom at a re-entrant angle of substantially 45° , a pair of sheet metal panels each having a flat marginal flange projecting at an angle of substantially 45° from a flat marginal portion of the panel, this latter portion fitting against

- the flat wings of the channel respectively with the salient angle of the panel fitting into the re-entrant angle of the channel and with the flange of the panel fitting against the flat bottom of the channel with the edges of the two flanges contiguous to each other, a combined clamping and holding strip having a flat surface along its middle to fit against the flat flanges of both of the panels and having a pair of flat marginal surfaces at a salient angle of substantially 45° to its middle flat surface with these flat angular marginal portions of such strip fitting against the flat surfaces of the marginal portions of the panels respectively and with the salient angles of this strip fitting into the re-entrant angles formed by the panel flanges respectively, and a series of headed screws passing through the said strip between the contiguous edges of the panel flanges and screwing into the corner piece frame part, whereby the margins of the two panels will be firmly but detachably secured to the corner frame piece.
14. In an article of furniture, the combination of an outer metal corner piece forming a rigid frame part having in its inner side a channel with flat surfaces forming a re-entrant angle of substantially 45° , a sheet metal panel having an angularly bent edge portion providing flat surfaces at an angle fitting into the re-entrant angle of the channel and against its flat surfaces, a combined clamping and holding strip having a clamping face with a salient angle and flat surfaces fitting into the angle of the bent edge portion of the panel and against its flat surfaces, and a series of headed screws passing through the clamping strip free from the edge of the panel and screwing into the corner piece at its inner side for firmly holding the clamping strip against the angularly bent edge portion of the panel to cooperate with the angular channel for thereby firmly but detachably securing the latter to the corner frame piece.
15. In an article of furniture having a series of immediately adjacent superposed drawers, a sheet metal drawer front having in combination therewith a hollow top edge reinforcement formed in the same piece therewith to include an outer top rib in the form of a bead and an inner top ledge wider inwardly than the outward depth of the rib and which together with the rib constitutes a hollow stiffening rail along the top edge of the drawer front, and a hollow combined clearance ridge and lower front corner reinforcement for the drawer formed in the same piece with the drawer front on a marginal extension thereof below the bottom of the drawer to include a lower corner front rib in the form of a bead and a terminal reinforcing flange portion which extends rearwardly and upwardly below the lower side of the drawer bottom.
16. The invention defined in claim 15, in which the said bead formed by the said lower front corner rib projects forwardly to the outside to a greater extent than does the said bead formed by the said upper rib at the top edge of the drawer front so as thereby to overhang the latter on the front of a drawer next below.
17. In an article of furniture, the combination of a rigid metal frame bar forming a horizontal front rail of the frame of such article, and a horizontal sheet metal panel which at its forward margin is bent around the said frame bar rail thereby firmly to secure the panel to this rail.
18. In an article of furniture, the combination of a rigid flat metal bar extending horizontally on edge with its flat sides vertical to form a front rail part of the frame of such article, and a horizontal sheet metal panel in alignment with the upper edge of the said frame bar rail to extend rearwardly therefrom and having its front margin bent downwardly at the front of this rail and thence rearwardly and upwardly around the rail and terminating in a rearwardly extending flange beneath the said panel thereby to provide a firm support for this panel at the front as well as also to enclose and cover the said frame part rail.
19. A drawer having a sheet metal side wall bent to form a supporting channel at its outer side in the upper portion thereof, and a hollow reinforcement along the upper edge of the wall formed by bending the upper edge portion of the wall in such manner that the lower side of the said hollow reinforcement constitutes the upper side of the said channel.
20. A drawer having a sheet metal side wall bent inwardly to form a supporting channel at the outer side in the upper portion thereof, and a hollow reinforcement formed along the upper edge of the wall by an upward continuation of the bottom of the channel with this upward continuation bent outward and thence downward and thence inward so that thereby the lower side of the said hollow reinforcement constitutes the upper side of the said channel.
21. A drawer having a sheet metal side wall bent inwardly to form a supporting channel at the outer side in the upper portion thereof, and a hollow reinforcement formed along the upper edge of the wall by an upward continuation of the bottom of the channel with this upward continuation bent first outward and thence downward and thence inward and thence again downward along the bottom of the said channel so that thereby the lower side of the said hollow reinforcement constitutes the upper side of the said channel with the downwardly bent extension from the lower side of such reinforcement lying against the bottom of the channel.

22. In an article of furniture, the combination of a rigid metallic corner upright having its inner face longitudinally channeled, a sheet metal panel having an edge portion entering the channel face and shaped and detachably secured thereto, and a leg member underneath the upright and having a portion supporting the upright and an upward extension from said portion fitting into the channel face of the upright below said portion of the panel and permanently secured to said face.

15 In witness whereof, I hereunto subscribe my signature.

LOUIS H. MORIN.
